UNITED STATES PATENT OFFICE.

WILLIAM H. LEONARD, OF PHILADELPHIA, PENNSYLVANIA.

FIRE-HYDRANT.

SPECIFICATION forming part of Letters Patent No. 287,554, dated October 30, 1883.

Application filed May 24, 1883. (No model.)

To all whom it may concern:

Be it known that I, WILLIAM H. LEONARD, a citizen of the United States, residing at Philadelphia, in the county of Philadelphia and State of Pennsylvania, have invented certain new and useful Improvements in Fire-Hydrants, of which the following is a specification, reference being had therein to the accompanying drawings.

10 My invention relates to fire-hydrants; and the improvement consists in providing means whereby a full flow of water, free from any obstruction either of the valve-rod or from the mechanism of the valve itself, is secured.

15 In the accompanying drawings, in which similar letters of reference indicate like parts, Figure 1 shows an elevation of my improved fire-hydrant. Fig. 2 is a section of the same, showing the hydrant open and the water passing through in the direction indicated by the arrows.

20 A represent the outer casing of the hydrant; B, a movable water-way inside the outer casing; C, a screw surrounding the water-way and secured thereto. The screw C may be integral with the water-way B, or attached to it by any convenient means; D, a beveled cog-wheel surrounding the screw C and working into and with it. E is another beveled cog-wheel gearing into the wheel D; b, the bearing of the wheel D. This bearing passes through the outside casing of the hydrant, and on the outer end thereof is square, so that a wrench or similar device may be fitted thereto. F is a water-supply pipe connecting with the hydrant. H is a valve-seat secured into the lower part of the outer casing A, and surrounding the movable water-way. K is a valve on the end of the movable water-way. c is a small opening at the bottom of the movable water-way, to allow the water remain-

ing in the water-way after the hydrant is closed to escape and pass through the opening c in the outer casing into the ground. d is a feather strip on one side of the lower end of the water-way and passing through a corresponding slot in the valve-seat, and thus preventing the said water-way from revolving when it is being raised or lowered. The hydrant being turned on, and the water flowing, as shown in Fig. 2, to stop the flow of water a wrench, crank, or similar device is fitted to the square end of the bearing b, and the wheel E thus made to revolve. This communicates the motion to the wheel D, which in turn operates on the screw C, thus raising the water-way B until the valve K is brought up to the valve-seat H, when the water is securely cut off, any water remaining in said water-way passing off through the openings c c'.

Having thus described my invention, what I claim as new, and desire to secure by United States Letters Patent, is—

1. In a fire-plug, the movable water-way B, provided with the screw C, in combination with the beveled cog-wheels D and E, substantially as and for the purposes shown and described.

2. In a fire-hydrant, the combination of the supply-pipe F and casing A with the movable water-way B, provided with an opening near the bottom and having below the opening an extended flange forming the valve K on its upper face, the valve-seat located above the supply-pipe F, and means for raising and lowering the water-way, as set forth.

In testimony whereof I affix my signature in presence of two witnesses.

WILLIAM H. LEONARD.
